UNITED STATES PATENT OFFICE.

HUGH B. SMITH, OF UNIVERSITY PLACE, NEBRASKA.

FOLDING TABLE.

1,422,313.

Specification of Letters Patent. Patented July 11, 1922.

Application filed March 25, 1919. Serial No. 284,897.

To all whom it may concern:

Be it known that I, HUGH B. SMITH, a citizen of the United States, residing at University Place, in the county of Lancaster 5 and State of Nebraska, have invented certain new and useful Improvements in Folding Tables, of which the following is a specification.

The invention relates to a table which is 10 designed with a special reference to folding into a compact form for storage and convenience of handling, thereby adapting the same to be readily carried in a vehicle to be used in the open for supporting food, for playing 15 games or for other uses for which a table is generally employed.

The drawings illustrate a preferred embodiment of the invention. However, it is to be understood that in adapting the same 20 to meet different conditions, various changes in the form, proportion, and minor details of construction may be resorted to without departing from the nature of the invention as claimed hereinafter.

25 Referring to the accompanying drawings, Fig. 1 is a side view of a folding table embodying the invention, showing the same set up for use.

Fig. 2 is an end view.

30 Fig. 3 is a view similar to Fig. 2 having the legs folded.

Fig. 4 is a side view with one of the legs partly folded and the dotted lines indicating the movements of the legs when folding 35 and unfolding the same.

Fig. 5 is a detail view of the table in folded position.

Fig. 6 is an end view of the table as it appears when folded and having the textile top 40 wrapped about the frame structure.

Fig. 7 is an elevation of the folding brace of a leg section.

Fig. 8 is a horizontal section on the line 8—8 of Fig. 2.

45 Fig. 9 is a detail section on the line 9—9 of Fig. 2.

Fig. 10 is a sectional detail, showing the manner of connecting a leg member to a side bar.

50 Fig. 11 is a sectional detail of one of the side bars and the leg member connected thereto showing more clearly the manner of connecting the textile top to the side bars.

Fig. 12 is a view similar to Fig. 7, showing a modified form of brace.

Corresponding and like parts are referred

to in the following description and indicated in the several views of the drawings by like reference characters.

The folding table is constructed in a manner to be reduced approximately to the form of a roll substantially, as indicated in Figs. 5 and 6 whereby it may be stored in a small space and conveniently handled. When the table is in compact form it may be placed 60 upon the floor of an automobile and serve the purpose of a foot rest. The top of the table is of textile and may be wrapped about the table structure, as indicated in Fig. 6, thereby holding the parts in compact arrangement. The frame work of the table is 65 preferably constructed of metal consisting of bars of suitable outline in cross section to provide a light, durable and strong frame work which will resist ordinary usage. 75

The table comprises side bars 1, folding leg sections A, folding braces B and a textile top C. The side bars 1 are of similar or like formation and have their upper edges recurved, as indicated at 2 for the two-fold 80 purpose of stiffening and reinforcing the side bars and to provide securing means for the top C. A rod 3 is slipped into a tuck or hem formed at each longitudinal edge or side of the top C and the reinforced edges 85 of said top are secured within the recurved or folded edge portions 2 of the side bars 1. This is indicated most clearly in Fig. 11. Each side bar 1 has a longitudinal slot 4 in each end portion and the longitudinal 90 slot 4 has a lateral extension 5 at its inner end which extends relatively in an upward direction and consists of a notch opening into the slot 4. The notch 5 receives the pivot fastening of a member of a leg section 95 and assists materially in holding the leg section in vertical position.

The leg sections A are of similar or like formation, each consisting of two bars 6 which cross and are pivoted at the point of 100 crossing, as indicated at 7. A suitable fastening 8 connects each of the bars or members 6 with an end portion of one of the side bars 1, the fastening 8 passing through the longitudinal slot 4 in which it is free to 105 run thereby forming an open seam tube. The fastening 8 is also adapted to enter the notch or lateral extension 5 of the longitudinal slot 4. In this manner the leg sections are connected to the side bars 1 in a manner to 110 have both a pivotal and a sliding movement which admit of the leg sections folding into

the plane of the side bars so as to occupy a position between them, as indicated in Figs. 5 and 6. A brace 9 pivotally connects each of the leg members 6 with an end portion of a side bar 1, the parts being so disposed and relatively proportioned as to admit of the leg sections occupying a position perpendicular to the side bars 1 or to lie in the plane of such side bars. When the leg sections are 10 in upright position or perpendicular to the side bars 1 the fastenings 8 enter the notches 5 and in conjunction with the braces 9 hold the leg sections in vertical position. When it is required to fold the leg sections the side bars 1 are moved to cause the fastenings 8 to clear the notches 5 after which the leg sections may be folded, as indicated by the dotted lines in Fig. 4, the fastenings 8 moving 15 outward in the longitudinal slots 4.

20 The folding braces B are of like formation, each consisting of two bars 10 and 11 which are pivotally connected near their inner ends, as indicated at 12 and which have their outer ends pivoted to the bars 6, as indicated at 13. One of the bars, as 11, has an end portion extended and adapted to engage over an edge portion of the bar 10, as indicated at 14, thereby holding the bars 10 and 11 in extended position whereby to hold 25 the leg sections spread and the top C taut. The braces B are adapted to break joint upward. The bars comprising the braces B may be straight or curved, the latter formation being indicated in Fig. 12. It will be noticed that the legs are pivotally connected nearer the lower ends which is done to increase the leverage of the leg's section when the top is drawn taut.

In practice the table when set up appears 40 substantially, as indicated in Figs. 1 and 2, that is, the bars or members 6 comprising the leg sections are spread and are held apart by means of the braces B and said leg sections are disposed in upright position, 45 thereby holding the top extended in horizontal position. When the table is reduced to compact form the members or bars 6 comprising the leg sections are folded, as indicated in Fig. 3 and the folded leg sections 50 occupy a position between the side bars 1, as illustrated in Figs. 5 and 6 and the textile top C is wrapped about the frame struc-

ture, as shown most clearly in Fig. 6. This results in the formation of a bundle having the approximate form of a roll which may 55 be conveniently handled and readily stored so as to be out of the way. When the table is to be carried in an automobile or other vehicle it may be placed upon the floor and utilized in the capacity of a foot rest as 60 will be readily understood.

The foregoing description and the drawings have reference to what may be considered the preferred, or approved form of my invention. It is to be understood that I may 65 make such changes in construction and arrangement and combination of parts, materials, dimensions, et cetera, as may prove expedient and fall within the scope of the appended claim.

Having thus fully described my invention, what I claim as new and desire to secure by Letters Patent is:—

A table including in combination, a pair of folding leg sections each consisting of two 75 bars which are pivotally connected near their lower ends, two side bars having their upper ends recurved to provide an open seam tube with a slot near each end having a lateral extension, a pivot fastener fixed to each leg 80 end arranged to work in a slot, a brace bar pivotally fixed to each end of said side bars and leg sections to hold said legs perpendicular, folding braces each consisting of two bars pivotally connected at their inner ends 85 and having their outer ends pivotally fixed to said leg sections one of said braces having its end extending over to provide a hook for engagement with said other brace, a fabric top having side seams for engagement with 90 said open seam tubular members, a rod held in said seams and said tubular members, and a pivotal connecting member uniting said leg sections near the lower ends whereby increasing the leverage of said leg sections or in 95 holding said top taut, all as and for the purpose set forth.

In testimony whereof I affix my signature in presence of two witnesses.

HUGH B. SMITH.
